STILE FOR A SLIDING GLASS DOOR

William J. Horgan, Jr., Pittsburgh, Pa., assignor to Pittsburgh Plate Glass Company, Pittsburgh, Pa., a corporation of Pennsylvania

Filed Mar. 8, 1962, Ser. No. 69,144

Term of patent 14 years

(Cl. D13—6)

FIG. 1 is a perspective view of a stile for a sliding glass door embodying my new design, as seen from a point adjacent one end thereof.

FIG. 2 is an end view of the same from the same end at reduced scale.

FIG. 3 is an end view of the stile from the other end thereof, also at reduced scale.

In FIG. 1 a portion is broken away intermediate the ends to show indeterminate length of the stile.

The dominant features of my design reside in the portions shown in full lines on the drawing.

I claim:

The ornamental design for a stile for a sliding glass door, as shown and described.
